UNITED STATES PATENT OFFICE.

HENRY P. CLAUSEN, OF MOUNT VERNON, NEW YORK, ASSIGNOR TO WESTERN ELECTRIC COMPANY, INCORPORATED, OF NEW YORK, N. Y., A CORPORATION OF NEW YORK.

TELEPHONE SYSTEM.

1,246,882.

Specification of Letters Patent.

Patented Nov. 20, 1917.

Application filed December 29, 1916. Serial No. 139,561.

To all whom it may concern:

Be it known that I, HENRY P. CLAUSEN, a citizen of the United States, residing at Mount Vernon, in the county of Westchester 5 and State of New York, have invented certain new and useful Improvements in Telephone Systems, of which the following is a full, clear, concise, and exact description.

This invention relates to telephone 10 change systems, and more particularly to the arrangement of selective switches within such a system.

The object of the invention is to provide means for equalizing, as far as possible, the 15 service performed by the individual connector switches, and in so doing to reduce the total number of such switches required.

A feature of the invention is an over-flow connector switch which may be mul- 20 tipled to several levels of a preceding selector switch, and the provision of means within such over-flow connector switch for automatically identifying the level of such selector switches from which a call is ex- 25 tended.

In the drawings, Figure 1 is a front elevation of the structural mechanism of an over-flow connector switch; Fig. 2 is a top plan view of the same; Fig. 3 is a diagrammatic representation of the usual designation of the line terminals in an ordinary connector switch; Fig. 4 is a diagrammatic representation of the arrangement of line terminals in an over-flow connector switch 30 designed to serve four levels of a preceding selector switch; Fig. 5 is a diagrammatic representation of the arrangement of line terminals in an over-flow connector switch 35 designed to serve five levels of a preceding selector switch; Fig. 6 is a diagrammatic representation of the connections between a selector switch and an over-flow connector switch serving four levels of this selector switch; and Fig. 7 is a diagrammatic representation of the trunking arrangements 40 within a system where over-flow connectors serving four levels of a preceding selector switch are used.

Referring now especially to Figs. 1 and 2, 45 these represent a structural embodiment of the invention whereby the desired object is obtained and shows details of a selective switch of the up-and-around type and means for automatically identifying the group of 50 lines to which a call is extended. The

switch employs a shaft 1, formed in its upper portions in a rotary ratchet member 2, a vertical ratchet member 4, and a shaft 5 with a collar 6 attached at its upper end. Slidably mounted on the upper portion of 60 the shaft are two collars 7 and 8 designed to be brought in engagement with the collar 6, and thereby elevate the brush shaft, in accordance with the energization of magnets 13 and 14, respectively, one or two steps to 65 predetermine the position of the brushes. Also slidably mounted on the shaft is a rotary position-determining ratchet 9 held in permanent angular relation with the shaft through the member 3 working in the groove 70 G. Secured to the shaft 1, below these various ratchet members, is a brush carriage 10 carrying a brush set 11 shown in association with a bank of contacts 12.

A frame to which the switch parts are 75 mounted is shown in part at F. Securely mounted to this frame are two magnets 13 and 14. The energization of magnet 14 is designed to lift the shaft one vertical step by the action of collar 8, while the energi- 80 zation of magnet 13 is designed to lift the shaft two vertical steps by the action of collar 7. Subsequent elevation of this shaft, through its ordinary stopping means, causes the shaft 5 to slide through the collars 7, 8 85 and 9.

Also mounted on the frame F are two magnets 15 and 16. The energization of magnet 15 is designed to move the shaft one 90 rotary step, while the energization of mag- 95 net 16 is designed to move the shaft two rotary steps. When not in operation the pawls P¹ and P², controlled by these magnets, do not interfere with other motions of the shaft.

A magnet 17 also secured to the frame F, actuates an armature and a pawl 18 to co-operate with the notches of the vertical ratchet member 4 in such a manner that, according to an easily made adjustment, the 100 shaft 1 may be elevated either two or three vertical steps at a time. In a similar manner a rotary magnet 19 is provided and may be so adjusted as to rotate the shaft either two or three rotary steps at a time. 105 A member 20 controlled by magnet 21 consists of two pawls mounted on a shaft 22 for engagement with the teeth of the vertical and rotary ratchet members in such a way, that, after actuation of the shaft by 110

the magnets 17 and 19, the position attained will be held until the release of the switch. This is accomplished through the energization of magnet 21.

Fig. 3 shows the usual numbering arrangement of the line terminals in a connector switch. There are usually ten levels and ten sets of contacts in each level. The first level contains lines designated from 11 to 20 inclusive; the second level contains lines designated from 21 to 30 inclusive; and so on.

In Fig. 4 a different arrangement is shown. In this case it will be noticed that in the first level and in the odd sets of terminals in this level, lines in the zero hundred from 11 to 20 inclusive appear. If then the brushes of the switch are set on the first level and then driven in a rotary direction, they must pass two sets of terminals at each step, in order to keep within the same hundreds designation. It will be noticed that the even terminal sets belong to the third hundreds designation. The same is true in regard to the vertical arrangement. In other words, the zero and third hundreds designations appear only in the odd vertical levels, while the one and two hundreds designations appear in the even levels. Thus, with twenty levels and twenty rotary positions, four hundred lines are served in a connector switch of this type.

In Fig. 5 a scheme is shown whereby five hundred lines may be served. In this case the zero and third hundreds designations appear in the first, fourth, seventh, tenth, thirteenth, sixteenth, nineteenth, twenty-first, twenty-fourth, twenty-seventh and thirtieth levels, and in these levels the zero hundreds designation appears in the odd positions, and the three hundreds designation in the even positions. The one hundreds, two hundreds, and four hundreds designations are arranged in a corresponding manner.

Suppose the scheme shown in Fig. 4 is used. If a call is extended by a selector switch, of which part of a bank of contacts SS is shown in Fig. 6, and in which the first level indicated by the first three vertical rows of contacts, is selected, and if the over-flow connector switch whose contact bank is designated OC¹ is found idle, then the talking strands of the connection will be extended to conductors 20 and 21, and in turn to the brushes b¹ and b². The test conductor from the selector switch will be extended over the conductor 22, and brush b³, and upon the seizure of the connector switch the vertical and rotary magnets would proceed in the usual manner to drive the brushes b¹, b² and b³ into association with the terminals of the desired line.

It should be noted here that the normal position of the brushes is such that one dou-

ble step in each direction must be taken to make connection with a set of terminals, and that if the primary and secondary magnets are actuated and the preliminary stepping magnets have not been energized, then the brushes will at the end of each step rest in turn on the first, third, fifth and all other odd numbered rows. If, however, the preliminary stepping magnets have been energized as will be more fully explained later, then the brushes will in turn rest on the terminals in the even numbered rows. In the present case each step taken by the switch in each direction will cause the brushes to move over two sets of terminals, so that should three vertical steps and two rotary steps be taken, the brushes will finally rest on the third set of terminals in the fifth level, and the line designated by the zero hundred and the thirty-second set of terminals in such hundred will be selected.

If, however, the call should be extended over the second level of the selector switch SS, the test conductor will be extended over the conductor 23 instead of 22, and through the magnet V¹ before joining the brush b³. The magnet V¹ is one of two windings of magnet 14, either of which will energize magnet 14 and cause the shaft 1 to be elevated one vertical step. Upon the seizure of this over-flow connector switch one vertical step will immediately be taken, and upon the receipt of the external impulses the action before described will take place, only with this difference: The brushes now having been stepped one vertical step by the magnet 14, if three double steps are made under the control of the magnet 17, and two rotary steps are made under the control of magnet 19, a line in the sixth level and in the third rotary position will be selected, such line being the thirty-second line in the first hundred.

If a call comes in on the third level of the selector switch, then the test conductor will be extended through the conductor 24, the magnet V² and magnet R in series, before the brush b³ is reached. The magnet V² represents the other winding of the magnet 14 and the magnet R represents the winding of magnet 15. Hence, the seizure of this connector switch results in the immediate movement of such switch one vertical step and one rotary step. The latter movement of the brushes, in response to the external impulses will bring the brushes finally to rest on the fourth set of contacts in the sixth level, or rather the second even set of contacts in the third even level, and in this manner the thirty-second line in the second hundreds designation is reached.

In a similar manner the extension of a call over the fourth level extends the test conductor over conductor 25, and in this case through magnet R only, to brush b³. Upon

the seizure of the switch OC¹, one rotary step only is taken, the brushes being left in their original vertical position. Upon the receipt of external impulses the brushes will finally come to rest in connection with the second even set of terminals in the rotary direction, and the third odd set of terminals in the vertical direction, and the thirty-second line in the third hundreds 10 will be selected.

This arrangement allows of multiplying only four levels in a selector switch. Since such switches are usually provided with ten levels, it will be seen that a special arrangement of such over-flow switches must be made, which arrangement will be explained in detail in connection with Fig. 7.

The arrangement of lines indicated in Fig. 5 will accommodate five levels of a selector switch, and, therefore, only two over-flow connector switches are needed to serve such a switch. It should be noted, in connection with this figure, that the corresponding hundreds are found in every third 20 level, and hence when such a connector switch is seized either two, one or no preliminary vertical steps may be taken, and the primary magnet of such switch must be arranged to elevate the brush carriage over 25 three steps of contacts during each energization. The preliminary steps may be accomplished either by extending the test conductor directly into the test brush, as over conductor 22 to the brush b³, or by extending 30 the test conductor over one winding of the magnet 14 or over one winding of the magnet 13. The arrangement for the preliminary rotary displacement is the same as before, although provision is made in the 40 structure of this switch for a double displacement, which might be used if a connector switch were to serve nine different hundreds instead of five different hundreds as here shown.

Referring now especially to Fig. 7 which shows the trunking arrangement used in connection with a four-hundred-point over-flow connector switch. SS¹, SS², SS³, and SS⁴ represent selector switches which may 45 serve lines in a group, say, from 1000 to 2000. SS⁵, SS⁶, SS⁷ and SS⁸ are selector switches which may serve a group of lines, say, from 0 to 1000. The first four levels of the selector switches SS⁵, SS⁶, SS⁷ and SS⁸ 50 would then lead to connector switches serving lines from 0 to 400. The second four levels would lead to connector switches serving lines from 400 to 800. The last two levels of these selector switches and the first 55 two levels of the selector switches SS¹, SS², SS³ and SS⁴, lead to lines 800 to 1200. The third to the sixth levels, inclusive, in selector switches SS¹, SS², SS³ and SS⁴, lead 60 to lines 1200 to 1600, and the last four 65 levels of these selector switches lead to lines

1600 to 2000. Thus, five four-hundred-point over-flow connector switches serve two groups of preceding selector switches.

It is intended, as indicated in the selector switches SS¹ to SS⁸, that the first five sets 70 of terminals in each level of each selector switch shall lead to connector switches CS¹, CS², etc., in the ordinary and well-known manner. Connection between such selector and connector switches is indicated by the 75 cables C¹, C², C³ and C⁴. The over-flow connector switch OC³ is intended to serve the lines terminating in the connector switches CS¹ to CS⁴, which lines, as previously mentioned, might be designated from 80 1600 to 2000.

The sixth to the tenth set of contacts in each level of each selector switch SS¹ to SS⁸ is intended, and shown here, as leading to a four-hundred-point over-flow connector 85 switch. For instance, the last five pairs of contacts in the upper four levels in the selector switches SS¹ to SS⁴ lead over a cable C⁵ to the over-flow connector switch OC³.

A call being extended through the selector 90 switch SS¹ might either be extended to a connector switch CS² or, in case each of these single group connectors is busy, to a multi-group connector OC³. In the latter case the identity of the level of the selector 95 switch from which the call is extended will be preserved in the manner heretofore described by the preliminary setting of the brush set.

What is claimed is:

1. In a telephone system, telephone lines arranged in groups, selector switches, connector switches of a capacity to serve one group of lines each, connector switches of a capacity to serve a plurality of groups of 100 lines each, said selector switches being arranged to extend telephone lines both to single group connector switches and to multi-group connector switches, and means included in said multi-group connector 105 switches for automatically setting such switch on the terminals of a selected line in the proper group.

2. In a telephone system, telephone lines arranged in groups, selector switches, connector switches of a capacity to serve one group of lines each, connector switches of a capacity to serve a plurality of groups of 110 lines each, said selector switches being arranged in their primary movements to extend telephone lines to rows of terminals leading to connector switches serving different groups, and arranged in part of their secondary movements for extending telephone lines to particular connector switches 115 serving the same group and in another part of their secondary movements for extending telephone lines to particular connector switches of increased capacity serving the same groups, and means included in said 120 125 130

- 4 connector switches of increased capacity for automatically identifying the particular group to which the said selector switches in the first part of their secondary movements 5 are arranged to select.
3. In a telephone system, telephone lines arranged in groups, selector switches, connector switches of a capacity to serve one group of lines, connector switches of a capacity to serve a plurality of groups of lines, said selector switches being arranged in their primary movements to select a particular group of lines and being arranged in part of their secondary movements to 10 select a particular connector switch serving the selected particular group of lines and being also arranged in another part of their secondary movements to select a particular connector switch of increased 15 capacity serving both the selected particular group of lines and other groups of lines, and means included within said connector switch of increased capacity for automatically identifying the selected particular 20 group of lines.
4. In a telephone system telephone lines arranged in groups, selector switches, connector switches of a capacity to serve one group of lines, connector switches of a capacity to serve a plurality of groups of lines, said selector switches being arranged to select by a primary movement a group of connector switches serving a particular group of lines including single group connector switches and multi-group connector 25 switches and arranged to select by a secondary movement a particular one in said group of connector switches, and means included in said multi-group connector switches for automatically distinguishing between the several groups of lines thus served.
5. In a telephone system, groups of telephone lines, single group selective switches, multi-group selective switches, and means included in said multi-group selective switches for automatically distinguishing between the several groups of lines served thereby.
6. In a telephone system, groups of telephone lines, single group selective switches, multi-group selective switches, and means individual to said multi-group connector switches for automatically directing the selection of a line within a preselected particular one of the several groups of lines 50 served thereby.
7. In a telephone system, groups of telephone lines, single group connector switches, multi-group connector switches, selector switches arranged to extend telephone lines 60 to connector switches serving particular groups of lines, and means individual to said multi-group connector switches for preserving the identity of the group of lines selected by said selector switches. 65
8. In a telephone system, groups of telephone lines, selector switches for interconnecting said lines, single group connector switches, multi-group connector switches, sets of terminals in said selector switches 70 arranged in rows, sets of terminals in each row leading to single group connector switches serving the same group, other sets of terminals in each row leading to multi-group connector switches serving the same 75 groups including the group served by the single group connector switches in that row, and means individual to the multi-group connector switches for preserving the identity of the row of terminals from which 80 said telephone lines are extended.
9. In a telephone system, groups of telephone lines, single group connector switches, multi-group connector switches, terminals in said multi-group connector switches arranged in vertical and horizontal rows, said 85 terminals of each group being interspersed with the terminals of each other group and arranged to recur periodically, and means individual to said multi-group connector 90 switches for automatically causing said switch to extend telephone lines to others included in one or another of the groups of lines served thereby.
10. In a telephone system, telephone lines 95 arranged in groups, selector switches, connector switches of a capacity to serve one group of lines each, connector switches of a capacity to serve a plurality of groups of lines each, said selector switches being arranged to extend telephone lines to rows of terminals, certain terminals in each row being wired to single group connectors serving the same group of lines, other terminals in each row being wired to multi-group 100 connectors serving other groups in addition to the group served by said single group connectors, and means individual to said multi-group connectors for automatically 105 directing the setting of such connector within the group of lines served by the single group connectors wired to the row of terminals from which a line is extended.
- In witness whereof, I hereunto subscribe my name this 28th day of December A. D., 115 1916.

HENRY P. CLAUSEN.
